UNITED STATES PATENT OFFICE.

THEODORE F. OECHSLE AND ALBERT S. BANCROFT, OF PHILADELPHIA, PENNSYLVANIA.

WINDOW-OPERATING DEVICE.

1,195,258.

Specification of Letters Patent. Patented Aug. 22, 1916.

Application filed September 30, 1915. Serial No. 53,212.

To all whom it may concern:

Be it known that we, THEODORE F. OECHSLE and ALBERT S. BANCROFT, of Philadelphia, in the county of Philadelphia and 5 State of Pennsylvania, have invented certain new and useful Improvements in Window-Operating Devices, whereof the following is a specification, reference being had to the accompanying drawings.

10 The invention relates to an improved device for opening and closing windows or sashes, and one adapted to hold the sash open or closed or in any intermediate position, and more particularly to that class of 15 devices which serve to operate simultaneously a series of closures.

It is a further object of our invention to provide a simple but effective mechanism, rigidly supported at the operating points, 20 and capable of exerting ample force for controlling the sashes without distortion of the parts. Heretofore, such mechanisms have employed longitudinally movable operating rods directly connected to the arms and 25 levers for opening and closing the individual sashes, with such construction, however, the lateral strains exerted by the weight of the sashes tend to distort the operating rods, which greatly impair or destroy the effectiveness 30 of the device. It is, therefore, important to do away with such lateral strains.

To this end, we employ longitudinally movable operating rods provided with a number of toothed racks intermeshing with 35 rigidly pivoted geared pinions with which the arms and levers of each individual window operating mechanism are equipped, so that the main operating rods are free from any lateral strain and any motion thereof is 40 equally transmitted to all sashes.

Referring to the accompanying drawings, Figure I, is an inside elevation of a window structure conveniently illustrating the adaptation of our invention thereto. Fig. II, 45 represents a horizontal sectional view indicated by the arrows II-II in Figs. I and III. Fig. III, illustrates a cross sectional view, the plane of section being designated by the arrows III-III, in Fig. I.

50 Mounted in the frame 1, are a series of sashes 2, which may be pivoted at 3, or in any convenient manner, provided that the opening edges of the sashes all lie in the same straight line. Loosely journaled in

the brackets 5, which are attached to the 55 sashes at a point remote from that at which they are hinged, are links 6, which serve to connect the sashes with the operating mechanism. These links are in turn pivoted at 7, and 8, to the arms 9, and 10, respectively, 60 both of which are pivoted on shaft 11, in upper and lower portion. This shaft is supported in a bracket or other supporting means 12, which is firmly attached to the frame 1, at a point between two adjacent 65 sashes.

Arms 9, and 10, are oppositely disposed on shaft 11, one leading to the sash on one side of the bracket and the other to the sash on the opposite side. In order that they 70 may both exert outward or inward pressure on their respective sashes, at the same time, they are provided with gear pinions 13, and 14, which may be rotated in opposite directions. These pinions engage toothed racks 75 15, and 16, respectively. Each rack is composed of upper and lower plates 17, and 18, united by screw bolts 19, by which they are clamped in position upon rods 20, and 21, so as to be rigidly attached thereto. The 80 racks are also prevented from getting out of alinement with their respective pinions by grooves 22, and 23, cut in brackets 12, which act as both supports and guides. In this way bracket 12, supports both the operative 85 arms with their pinions and the rods with their racks, thereby carrying practically the entire weight of the structure, and at the same time furnishes a rigid pivot, so that the respective parts are subject to no strains 90 other than those due to the actual operation. Furthermore, any strains on the pivot 11, due to the weight of the sashes will be exerted in the direction away from the sashes, and can therefore in no way affect rods 20 95 and 21, which are placed on the side of the pivot toward the sashes.

Rods 20, and 21, are arranged parallel to each other and also parallel to the opening edges of the windows. At one end, they 100 are connected by a chain 25, which passes over an idler pulley 26, and serves to convey any motion transmitted to the one, to the other. At the other end they are connected to cross heads 27, and 28, by means 105 of guide rods 29, 29, and 30, 30, respectively. The cross heads are slidably mounted in a housing 32, and are engaged by shift-

- ing screws 34, and 35, which are placed between the guide rods 29, 29, and 30, 30, and in direct alinement with the rods 20, and 21. These screws are provided with intermeshing 5 spur pinions 36, and 37, and the actuating sheave 39, is made fast to the upper screw 36, so that when the sheave is turned the upper screw turns with it, but the lower screw turns in the opposite direction, resulting 10 in opposed longitudinal motion of the rods 20, and 21, transmitted through the cross heads 34, and 35. By means of the cross heads 27, and 28, and the guide 29, 29, and 30, 30, which straddle the shifting 15 screws, a purely longitudinal motion is produced, completely eliminating any possible torsional strain which might be transmitted to the rods 20, 21, and tend to get the racks and screws out of alinement.
- 20 In operation the sheave 39, is turned, and as has been explained, the screws rotate in opposite directions with the resultant opposed longitudinal motion of rods 20, and 21, so that racks 15, on the upper rod 20, 25 rotate pinions 13, in one direction, while pinions 14, are equally rotated but in opposite direction by racks 16, on the rod 21. This motion is imparted to arms 9, and 10. Since the arms are oppositely disposed, this 30 opposed motion either forces them both farther out or draws them nearer together, and through links 6, either opens or closes the window. It is obvious that similar motion will be equally transmitted to any number 35 of pinions which may be placed to intermesh with their respective racks, and, therefore, any number of windows may be controlled by a single longitudinal motion of rods 20, and 21.
- 40 By employing the rack and pinion construction, we not only greatly decrease the amount of lost motion which occurs in devices of this sort, but also eliminate any lateral strains on the operating rod due to 45 the weight of the sashes, since the only forces exerted on them are longitudinal. This prevents any distortion of these rods and keeps them from getting out of alinement, a very important factor, especially when a 50 number of sashes are to be operated, and rods of some length are required. Furthermore, the rods slide between the grooves in the brackets 12, and pivots 11, and any strain on the pivots is away from the rack 55 which prevents the rack from jamming, so that there is always an easy channel for the rods to slide in, and one which will not be affected by the position of the sashes because it is entirely formed in the solid bracket 12.
- 60 Having thus described our invention, we claim:
1. The combination with a pivoted closure, and its support, of a longitudinally movable operating rod; a toothed rack carried thereby; an arm provided with a geared

pinion intermeshing therewith and a link pivoted to said arm and also to the member to be operated, a shifting screw attached to one end of said operating rod and means for rotating said shifting screw.

70

2. The combination with a pivoted closure and its support, of a longitudinally movable operating rod; a rack carried thereby; a bracket attached to said support; an arm provided with a geared pinion at one 75 end, pivoted in said bracket; said pinion intermeshing with said rack in such a way that the racks are on the side of the pinion toward the closure; and a link pivoted at one end to said closure and at the other to 80 the arm.

75

3. The combination with a pivoted closure and its support; of a pair of longitudinally movable operating rods; a toothed rack carried by each rod; an arm with a 85 geared pinion intermeshing with each rack, said arms being mounted on a single pivot and adapted to swing outwardly or inwardly when rotated in opposite directions; links pivoted to said arms and to said closure; and means whereby longitudinal motion transmitted to one rod causes the other rod to move longitudinally in the opposite direction, with consequent opposed rotation of said pinions, whereby both arms 90 move outwardly or inwardly.

90

4. The combination of a series of pivoted closures and their supports; supporting means attached to said supports; arms provided with pinions at one end pivoted therein, in upper and lower opposed relation; links pivoted to said arms and to said sashes; upper and lower operating rods, toothed racks carried thereby, intermeshing with the upper and lower pinions respectively, and means for causing the operating rods to move in opposite directions, whereby the upper pinions and arms will all move outwardly or inwardly in one direction, and the lower pinions and arms will all move 105 outwardly or inwardly in the opposite direction.

100

5. In a sash operating mechanism, a movable operating rod provided with toothed racks, operating arms provided with geared 115 pinions, intermeshing therewith, said racks comprising upper and lower plates attached above and below said operating shaft.

115

6. In a sash operating mechanism, the combination of a longitudinally movable operating rod, a toothed rack carried thereby, a rigidly supported bracket, a geared pinion pivoted therein intermeshing with said rack, and a groove cut in said bracket whereby said rack is supported and maintained in 120 alinement with said geared pinion.

120

7. In a sash operating mechanism, the combination of longitudinally movable operating rods, toothed racks carried thereby, rigidly supported brackets, geared pinions 130

pivoted therein intermeshing with said racks, and grooves cut in said brackets corresponding one to each rack, whereby said operating rods are supported and said racks 5 maintained in alinement with said geared pinions.

In testimony whereof, we have hereunto signed our names at Philadelphia, Pennsyl-

vania, this twenty-fourth day of September, 1915.

THEODORE F. OECHSLE.
ALBERT S. BANCROFT.
